MULTI-FEED KNITTING MACHINE

Robert Peel and Peter A. Mahler, Philadelphia, Pa., assignors, by mesne assignments, to The Singer Company, New York, N.Y., a corporation of New Jersey
Filed June 8, 1960, Ser. No. 34,799
4 Claims. (Cl. 66—42)

The present invention relates to circular knitting machines, and has particular application to knitting machines of this type for making sheer ladies' hosiery.

A primary object of the present invention is to provide a knitting machine which enables a high rate of production without sacrificing quality in the final product.

Another important object of the present invention is to provide a multiple feed knitting machine wherein the needle action at each feed station is substantially identical so as to reduce to a minimum the possibility of non-uniform loops which would otherwise result.

Still another object of the present invention is to provide a knitting machine having novel driving connections embodied therein which effect a positive drive of various components of the machine without danger of undesired lost motion and the like.

Still another object of the present invention is to provide a knitting machine of the stated character having four feeds and in which all four feeds operate simultaneously throughout the entire stocking including the make-up.

The invention provides a knitting machine including a novel cabinet for the supply yarns which maintains the yarns at the proper condition of relative humidity to insure optimum knitting conditions.

The present invention provides a knitting machine of relatively simple construction and operation which is fully effective to provide a stocking on four feeds.

All of the objects of the invention and the various features and details of the construction and operation thereof are more fully set forth hereinafter with reference to the accompanying drawings in which:

FIG. 1 is a fragmentary view in side elevation of the upper portion of a knitting machine embodying the present invention;

FIG. 2 is a plan view of that portion of the knitting machine shown in FIG. 1 with certain portions broken away to more clearly illustrate the construction thereof;

FIG. 3 is an enlarged sectional view taken on the line 3—3 of FIG. 1;

FIG. 4 is a view in side elevation of that portion of the machine shown in FIG. 3;

FIG. 5 is a sectional view taken on the angled section line 5—5 of FIG. 3;

FIG. 6 is a fragmentary view in side elevation of that portion of the machine shown in FIG. 3;

FIG. 7 is a local sectional view taken on the line 7—7 of FIG. 3;

FIG. 8 is a sectional view taken on the line 8—8 of FIG. 7;

FIG. 9 is a perspective view of the mechanism shown in FIG. 8;

FIG. 10 is a vertical sectional view through the knitting machine showing the driving connections to the knitting instrumentalities and controls;

FIG. 11 is an enlarged view of that portion of FIG. 10 showing the yarn-feed station;

FIG. 12 is a vertical section taken at right angles to FIG. 10 generally along the line 12—12 thereof;

FIG. 13 is a view taken on the line 13—13 of FIG. 12;

FIG. 14 is an enlarged sectional view taken on the line 14—14 of FIG. 10;

FIG. 15 is a further enlarged fragmentary view of that

2

portion of FIG. 14 illustrating the yarn clamp mechanism;

FIG. 16 is a sectional view taken on the line 16—16 of FIG. 15;

FIG. 17 is a detached perspective view of the mechanism shown in FIGS. 15 and 16;

FIG. 18 is an enlarged fragmentary view in side elevation showing the splicing control mechanism of the knitting machine shown in FIG. 1;

FIGS. 19 and 20 are enlarged sectional views taken on the lines 19—19 and 20—20 respectively of FIG. 18;

FIG. 21 is an enlarged fragmentary view taken on the line 21—21 of FIG. 18;

FIG. 22 is a sectional view taken on the line 22—22 of FIG. 21;

FIG. 23 is an enlarged sectional view taken on the stepped section line 23—23 of FIG. 18;

FIG. 24 is a sectional view taken on the irregular line 24—24 of FIG. 23;

FIG. 25 is a fragmentary sectional view taken on the line 25—25 of FIG. 24;

FIG. 26 is a fragmentary detached perspective view of the mechanism shown in FIGS. 23 to 25 with certain elements removed;

FIG. 27 is a fragmentary view taken on line 27—27 of FIG. 18;

FIG. 28 is a sectional view taken on the line 28—28 of FIG. 27;

FIG. 29 is a fragmentary horizontal section through the yarn supply cabinet shown in FIG. 1 with the yarn packages removed;

FIG. 30 is a sectional view taken on the line 30—30 of FIG. 29 with the yarn packages shown in broken lines;

FIG. 31 is a sectional view taken on the line 31—31 of FIG. 29;

FIG. 32 is a detached perspective view of the humidifying pan of the yarn cabinet shown in FIGS. 29 to 31 inclusive;

FIG. 33 is a development of the cylinder showing diagrammatically the travel of the jacks and the needle butts during the initial portion of the formation of the makeup courses of the stocking;

FIG. 34 is a diagrammatic representation of the position of the bits during the formation of the makeup courses diagrammed in FIG. 33;

FIG. 35 is a view similar to FIG. 33 showing the travel of the needle butts and jacks during the remainder of the makeup courses;

FIG. 36 is a view similar to FIGS. 33 and 35 showing the travel of the needle butts and jacks during the formation of the welt;

FIG. 37 is a view similar to FIG. 35 showing the travel of the needle butts and jacks during the formation of the transfer courses;

FIG. 38 is a view similar to FIG. 34 showing the position of the transfer bits during the formation of the transfer courses;

FIG. 39 is a view similar to FIG. 33 showing the travel of the needle butts and jacks during the formation of the plain stitches in the shadow welt, leg and foot portions of the stocking;

FIG. 40 is a view similar to FIG. 39 showing the formation of the mesh in the leg and foot portions of the stocking;

FIG. 41 is a development of the cylinder showing the jack and needle positions during the mesh knitting;

FIG. 42 is a detached representation of a set of jacks employed in the illustrated machine;

FIG. 43 is a diagrammatic representation of the dial showing the operation of the bits;

FIG. 44 is a diagram of the travel of the jacks during the mesh formation showing the jack slides.

FIG. 45 is a development of the cams cooperable with the jack slides to produce the mesh pattern;

FIG. 46 is a diagram of the mesh pattern produced by the cams developed in FIG. 45;

FIG. 47 is a diagrammatic representation of the mechanism controlling the jack slides for the formation of the mesh, and showing the arrangement of the jack circle;

FIGS. 48 and 49 are sectional views taken on the lines 48-48 and 49-49 of FIG. 47;

FIG. 50 is a diagrammatic representation of the needle circle cooperating with the jack circle shown in FIG. 47;

FIG. 51 is a fragmentary perspective view of the jack control mechanism shown in FIG. 47;

FIG. 52 is a perspective view of the stocking tube formed by the machine of the present invention;

FIG. 53 is a view of the tube after being formed into a stocking;

FIG. 54 is a perspective view of the stocking as seen on the leg; and

FIG. 55 is an enlarged stitch diagram of that portion of the stocking shown by the broken lines 55 in FIG. 53 showing the mesh stitch formed by the mechanism illustrated in the drawings.

The knitting machine of the present invention knits a stocking as a continuous uninterrupted tube, the needle circle rotating unidirectionally throughout the formation of the stocking. With stockings made in accordance with the conventional practice, the heel and toe of the stocking are made with pockets formed by oscillating the needle circle in these areas of the stocking. Such oscillation reduces the production of the machine, as well as requiring operation at a greatly reduced speed during knitting of the toe pocket and heel pocket. The formation of a stocking according to the conventional prior art method involves an approximate time of between 10 and 18 minutes according to the type of machine, whereas in accordance with the present invention, the time for the formation of the stocking is reduced to approximately 3 minutes.

As shown in FIG. 52, the stocking 61 as it comes from the knitting machine, consists of a straight, gradually tapering tube 62. When the stocking is subsequently finished, the toe is closed, for example by a seam 63 (see FIG. 53), and the stocking is shaped as shown in FIG. 54 to conform to the contour of the leg. The formation of the stocking is started on four feeds with a plurality of makeup courses corresponding in number to the number of feeds. Following makeup of the stocking, the knitting proceeds to form the welt 65, each feed feeding a heavy welt yarn, for example of 40 denier. The formation of the welt continues, the makeup courses being held on transfer bits generally in accord with the conventional practice. After the completion of the welt 65, a transfer course is formed into which the makeup courses are interknit to complete the formation of the welt as a double thickness of knitted fabric. Following the transfer course, the welt yarn is knit to form a multiplicity of courses of shadow welt 66. At the end of the shadow welt, the leg yarns are introduced, the leg yarns being of lighter denier than the welt yarns, for example 15 denier. The leg yarns continue knitting to form the leg 67 of the stocking. During the knitting of the leg, the needle cylinder and sinkers are gradually displaced downwardly relative to the needles to form stitches of decreasing length, thereby causing the leg of the stocking to taper inwardly. The knitting of the leg may be done with plain knitting, or if desired, a mesh or net stitch may be employed as shown in FIG. 55. At the end of the leg, splicing yarns are introduced on two of the four feeds to provide a reinforcement 68 in the area of the heel, the splicing yarns being knit-in only for a portion of the travel of the needles in the revolution of the needle circle and floated in the remainder of the travel. During the knitting of the heel reinforcement 68, the displacement of the cylinder may be arrested so that the remainder of the stocking is knit

as a cylindrical tube, forming the foot 69 of the stocking. At the end of the foot, the heavier yarns are again inserted on the four feeds to form a toe portion 70 of heavier weight. The toe portion is knitted until the stocking is completed at which time the yarn is pressed off and the completed stocking blank is withdrawn from the area of the needles by the take-up. The toe portion of the stocking is then closed by seaming and the extraneous end portions and the reinforcing yarn floats are sheared prior to finishing the stockings. The closed tube is further shaped and set during the finishing operation to conform to the desired contour.

Referring now to FIG. 1, the knitting machine of the present invention comprises a frame 100 having a needle cylinder 101 mounted therein for rotation about its axis. The needle cylinder is of substantially conventional construction having vertical slots therein slidably mounting needles 102, and jacks 103 for vertical movement. The needles 102 have short, intermediate and long butts 104, 105, and 106 as shown in FIG. 41, and are grouped as shown in FIG. 50. The jacks 103 have upper and lower butts 54 and 55 respectively for guiding engagement with the upper and lower edges of the jack cam track. The upper butts 54 of the jacks 103 are alternately long and short as indicated at 54a and 54b in FIG. 42 for a purpose more fully described hereinafter in connection with the makeup and transfer operation of the knitting machine.

Surrounding the needle circle 102, the frame 100 mounts a plurality, in the present instance four, feed stations 111, 112, 113, and 114, each having a plurality of feed fingers 115 (see FIGS. 10 and 11). The frame also receives the sinker ring 118 which is mounted on the cylinder 101, the sinkers being slidable in the ring 118 to operate in the conventional way with the feed fingers and needles to form the knitted tube.

The vertical displacement of the needles is controlled by needle cams, needle slides, and jack slides, selected ones of which are displaceable as more fully set forth herein-after. The knitting instrumentalities are controlled in a predetermined manner by a pattern chain 121, a pattern drum 122 (see FIG. 12), and a mesh cam bank 123 (see FIG. 2). The splicing control mechanism is provided at 124 to time the operation of the splicing feed fingers 115 during the formation of the reinforced heel patch or other areas.

The yarn is supplied to the yarn feed fingers 115 from a yarn supply cabinet 131 mounting a plurality of supply packages 132 and 135 of yarns of various weights and characteristics for forming the different portions of the stocking. In accordance with the invention, the yarn cabinet 131 includes a humidifying device 133 to maintain the supply of yarn in proper condition for knitting. The yarn from the packages 132 and 135 is directed by suitable guide means through tensioning devices indicated generally at 134 to the yarn feed fingers 115. The tensioning devices insure proper tensioning of the yarns to effect the formation of the knitted loops uniformly throughout the length of the stocking, subject to the gradual shortening of the stitches effected by adjustment of the needle cylinder relative to the needles.

A rotary dial 141 (see FIG. 10) is mounted concentric with the cylinder 101 within the needle circle 102. A stationary dial cap 142 overlies the dial. The rotary dial 141 mounts a series of bits 144 for radial movement upon rotation of the dial under the action of dial bit cams 145 (see FIGS. 11, 14 and 43). The dial cap also mounts suitable clamping and shearing mechanism 146 in the present instance, one mechanism for each of the four feeds. The clamping and shearing mechanism 146 is clearly illustrated in FIGS. 15 to 17 inclusive. Each mechanism 146 is operated in the conventional way by means of an operating linkage 147, to shear the yarn end which passes across the dial into the mechanisms following insertion or withdrawal of one of the yarns at each feeding station.

Referring now particularly to FIGS. 10, 12 and 13, the knitting machine is driven by a variable speed drive motor 150. The drive motor 150 drives a main drive gear 151 through a suitable gear train 152. The drive gear 151 drives a cylinder drive shaft 154 having a bevel gear 155 meshing with a ring gear 156 on the cylinder 101. The gears 155 and 156 insure that the cylinder is driven at the same rotary speed as the cylinder drive shaft 154. The cylinder drive shaft 154 also has mounted thereon splicing cams 157 and 158 of the splicing mechanism 124. A multilobe cam 160 is mounted for rotation with the drive gear 151, and the latter gear is operatively connected to a crank 161 which continuously oscillates on a shaft 162. The cam 160 and oscillating crank 161 cooperate to provide an intermittent drive for the pattern chain through suitable pawl mechanism 163 (see FIG. 13). The pattern chain, in turn, controls a connection from the oscillating crank 161 to the pattern drum 122 which effects intermittent advance of the latter in accordance with the control elements on the pattern chain. This drive mechanism is generally similar to that disclosed in U.S. Patent No. 2,927,447 of Mahler.

The dial 141 and the mesh cam bank 123 are driven from the cylinder 101. To this end, as shown in FIG. 10, a vertical shaft 165 is driven from a ring gear 166 on the cylinder 101. The shaft 165 has a worm 167 thereon which drives a gear train 168. The gear train drives a mesh cam shaft 169 which mounts the cam bank 123 (see FIG. 3). In the illustrated embodiment, the gear train 168 is constructed to drive the mesh cam shaft 169, one revolution for every eight revolutions of the cylinder.

At its upper end, the shaft 165 drives the dial through a dial gear train 170. The gear train 170 has been designed as clearly shown in FIG. 10 to limit the amount of axial play of the gears and thereby insure full mesh of the respective bevel gears and consequently positive driving connections without lost motion between the cylinder 101 and the shaft 172 of the dial 141. It is noted that a bearing collar firmly anchors the shaft against a rigid part of the superstructure 173 of the frame 100 to accommodate the axial thrust inherent in the operation of bevel gears. A gearing of this character is necessary to permit the superstructure 173 of the frame to be pivoted on the shaft 174 to afford access to the top of the cylinder 101. The driving connections thereby insure precisely concurrent rotation of the dial 141 with the cylinder 101.

As the drive mechanism rotates the needle cylinder, the needle cams and slides operate to displace the needles between the latch-clearing level, the tuck level and the stitch-draw level to effect knitting of the tube 61. As shown in FIG. 41, the needles travel from right to left past the feed stations 111, 112, 113, and 114. At each feed station, a stitch cam 180 is provided to engage the butts of the needles 102 and draw the needles down from an elevated level to the stitch-draw level. The stitch cam for the station 111 is designated 180-1; the stitch cam for the station 112 is designated 180-2; the stitch cam for the station 113 is designated 180-3; and the stitch cam for the station 114 is designated 180-4. Each feed station also includes a subsequent elevating cam surface adjacent thereto, to elevate the needles at least to the tuck level.

In accordance with the invention, each stitch cam 180 is fixed in position to intercept each needle butt as it passes the associated feed station. The stitch cams and the subsequent elevating cam surfaces are identical in contour in the location where it is most critical while the loop is opening the latch. By this construction, it is assured that the stitch formation at each feed station is identical. By eliminating the necessity for adjusting the stitch cams into and out of the path of the needle butts, the normal tolerances necessary to afford such adjustments are eliminated and continued operation of the machine does not affect the positioning of the stitch cams. This construction therefore insures that the stitch formed at each feed

station is precisely identical to the stitches formed at the remaining feed stations.

In order to precisely position the stitch cams 180 to obtain the precisely identical action required, suitable adjustments are provided as shown in connection with the stitch cam 180-4 in FIGS. 7 to 9 inclusive. As shown in these figures, the stitch cam 180-4 is mounted on the frame 100 by a bracket 182 and a mounting block 183 which is accurately adjustable on the bracket 182 by means of an adjusting screw 184. A micrometer adjustment is provided as clearly shown at 185.

Elevating cam surfaces are provided at the various feed stations to raise the needles from the stitch draw level to an elevated position. The elevating cam surface of each station may also serve the subsequent feed station as a clearing cam or tucking cam to condition the needles for the reception of yarn at the subsequent station. As shown in FIG. 41, the elevating cam surfaces are identical in contour in the critical location to control the velocity of the needle while the loop is opening the latch. In the present instance, the elevating cam surface for the station 111 comprises a clearing cam 186-1, having a groove 187 therein which may permit selected needles to remain at the stitch-draw level. The clearing cam 186-1 is fixed in position, and the selection may be accomplished by means of a clearing cam slide 188-1 which is displaceable into a position intersecting said groove and which thereupon displaces the needles onto the upper surface of the clearing cam 186-1. This upper surface elevates the needles to the latch-clearing position wherein the needles are conditioned to receive yarn from the feed station 112.

Upon passage through the station 112, the needles are elevated by the elevating cam surface 189-2 from the stitch-draw level to the tuck level. The surface 189-2 is a part of the fixed cam track of the needles rigidly united with the frame 100 of the machine. A clearing cam slide 188-2 is provided to selectively position the needles in either the tuck level or the latch-clearing level. If the clearing cam slide 188-2 is withdrawn sufficiently to permit needles to remain in the tuck level, such needles may be lowered to the stitch-draw level prior to passing the feed station 113 by means of a draw-down cam 191-2 which is displaceable into the path of the needles at the tuck level.

Upon passage of the needles through the feed station 113, they are elevated by an elevating cam surface 186-3 which operates to elevate all of the needles to the latch-clearing level prior to passing the feed station 114.

When the needles pass through the feed station 114, they are again elevated to tuck level by means of an elevating cam surface 189-4. From the tuck level, the needles are selectively elevated to the latch-clearing level by means of a clearing cam slide 188-4 which is displaceable into the path of the needles at the tuck level to elevate the same to the latch-clearing level. Needles which are not elevated at this point may be lowered to approximately the stitch-draw level by means of a draw-down cam 191-4 which is actuatable to selectively depress the needles. A retractable clearing cam 186-4 is positioned following the draw-down cam 191-4 to elevate the needles whose butts engage said cam to the latch-clearing position.

In the operation of the machine to knit a stocking such as shown in FIG. 52, the cams are adjusted to the position shown in FIG. 33 wherein the full line positions indicate the cams which are in position to engage the needle butts and the broken lines indicate cams which are retracted out of the path of the needle butts. In addition to the adjustment of the needle cams, the upper jack slides 195-1, 195-2, and 195-3, are advanced to intercept the travel of the alternate long upper butts 54a but not to an extent to intercept the path of travel of the intermediate short upper butts 54b.

The makeup of the stocking is initiated by first introducing the yarn at the feed station 113. The stocking is started on the intermediate butt needles 105 at the datum

line A in FIG. 50. Prior to entering the feed station 113 the alternate needles associated with the jacks having long butts 54a are elevated to the latch-clearing height at this station by means of the jack slide 195-3 (see FIG. 33) and the intermediate needles associated with the jacks having short butts 54b are displaced to the stitch-draw level by the draw-down cam 191-2. Thus, the alternate needles take yarn at the station 113 and form knit loops thereon. As the needle circle rotates, the entire set of needles are elevated to the latch-clearing height by the clearing cam surface 186-3 to take yarn at the station 114. The stitch cam 189-4 forms a full complement of loops on the needle circle and the cam surface 189-4 elevates the needles to the tuck level. The jack slide 195-1 again elevates the alternate needles associated with the long butt jacks to the latch-clearing height, and the intermediate needles are lowered to the stitch-draw level by the draw-down cam 191-4. As the alternate needles enter the feed station 111 at the latch-clearing level, the bits 144 are introduced therebetween by the bit cams 145, as shown 20 in FIGS. 34 and 43. The stitch cam 186-1 knits loops on the alternate needles and firmly engages the makeup courses on the transfer bits 144. The alternate needles are again raised to latch-clearing level as they leave the station 111, and the intermediate needles are retained at the 25 stitch draw level by reason of the slide 195-2, the intermediate needles tracking through the groove 187.

As the datum line A approaches the feed station 113 for the second time, the clearing cam slide 188-2 is advanced into the path of movement of the intermediate butt needles 105 so that during their second travel through the feed station 113, all of the needles are elevated to the latch-clearing height and a full complement of loops is formed at the third station 113. While the intermediate and long butt needles are passing the clearing-cam slide 188-2, it may be advanced to its fully inserted position wherein it engages the short butt needles as well as the intermediate and long butt needles. After this is accomplished, the upper jack slide 195-3 and the draw-down cam 191-2 are withdrawn as indicated by the broken lines 30 in FIG. 35.

Prior to the passage of the datum line A past the clearing cam 186-4, this cam is first inserted to engage the intermediate and long butt needles and elevate the same to the latch-clearing position as shown in FIG. 35, and 35 then fully inserted. Prior to passage of the datum line A past the first feed station 111, to the clearing cam slide 188-1 is inserted in like manner, and when this cam is fully inserted, the upper jack cam 195-2 is withdrawn as indicated in broken lines in FIG. 35.

When the datum line A passes the feed station 113 for the third time, eight courses have been formed and the four feed stations continue knitting on all needles. During the formation of the welt, the draw-down cam 191-4 is withdrawn.

In order to form a transfer course following the completion of the knitting of the welt, the draw-down cam 191-4 is reinserted to depress the intermediate needles to the stitch-draw level. The bit cams 145 advance the bits as shown in FIGS. 38 and 43 to overlie the depressed intermediate needles so that the clearing cam 186-4 elevates the intermediate needles into engagement with the bits and the subsequent withdrawal of the bits by the bits cams, interlocks the makeup courses with the transfer course to complete the formation of the welt.

Following the completion of the welt, the shadow welt may be formed with plain stitches as shown in FIG. 39. To accomplish this, the clearing cam slide 188-4 is fully inserted to elevate all of the needles at that point for plain knitting and the draw-down cam 191-4 and the clearing cam 186-4 may be withdrawn. The cams are retained in this position for as long as it is desired to knit plain fabric.

When it is desired to form mesh fabric, alternate courses are knit plain and the intermediate courses are 70

knit with tuck stitches on every fourth needle (see FIGS. 46 and 55). In the present instance, the feed stations 112 and 114 operate to produce the plain knit courses and the feed stations 111 and 113 operate to produce the mesh courses. To accomplish this, the clearing cam slides 188-2 and 188-4 are retracted out of the path of the needle butts and the elevation of the needles between the tuck level and the latch-clearing level is controlled by the jacks. The jack selection mechanism of the present invention is generally similar to that disclosed in U.S. Patent No. 2,872,796 of Peel.

In accordance with the plan of the Peel patent, in the present instance the jacks are arranged in three groups, B, C, and D (see FIGS. 42 and 47). These three groups comprehend all of the jacks of the circle with the exception of one, numbered 201, which differs from all the others and which lies between and separates the series B and C. The groups B and D are associated with the needles having long and intermediate butts 105 and 106 and include jacks having short butts 204. The group B is provided with auxiliary butts 205 as shown in FIG. 42. The group C comprises jacks having long butts 206 and is associated with the needles having short butts 104. In accordance with the teaching of the Peel patent, the jack slides 203-1 and 203-3 are operated to engage with the butts 204 to 206 of the jacks to elevate three out of every four needles to the latch-clearing level, the fourth needle being retained at the tuck level to form a tuck stitch at the subsequent feed station. As the datum line A which coincides with the jack 201 passes the jack slides 203-3, the slides are adjusted as described hereinafter to engage certain of the auxiliary butts 205 and thereafter alter the mesh sequence. The same adjustments occur with the slides 203-1 when the datum line passes them as indicated at A' in FIG. 47. The jack 201 is provided to preclude the possibility of any tuck stitch being formed on the needle associated therewith, so that during the change in the mesh sequence, it is impossible to have two tuck stitches adjacent one another in the same course. The mesh pattern is diagrammed in FIG. 46, the tuck stitches being designated at X. It is noted that the wale line of stitches 202 adjacent the datum line A is devoid of any tuck stitches in the present instance. This wale line is formed on the needle associated with the jack 201.

In accordance with the invention, the mesh slides 203-1 and 203-3 are controlled from the common mesh cam bank 123. The cam bank comprises a series of identical cams having high spots 207, intermediate spots 208 and low spots 209 respectively corresponding to the fully inserted position, the partially inserted or intermediate position, and the fully retracted position of the respective jack slides. As pointed out above, in the illustrated embodiment, the cam shaft 169 rotates one-eighth turn for every revolution of the cylinder so that one revolution of the cam bank requires eight revolutions of the cylinder or the formation of thirty-two courses in the stocking, of which sixteen are mesh courses and sixteens are plain courses.

The jack slides 203-3 are actuated directly by a series of cam followers 211 pivoted to the frame as indicated at 212. The jack slides 203-1 are actuated by a linkage 213 extending around the cylinder from cam followers 214 pivoted to the frame as indicated at 215 to operating levers 216 at the position of the jack slides 203-1. The cam followers 211 and 214 are positioned 90° apart, but as shown in FIG. 45, the upper two cams are offset from the lower two cams 135° in accordance with the angular position of the slides 203-3 and 203-1, bearing in mind that the ratio of speed of rotation is 8:1 between the cylinder and the cam bank. As shown in FIG. 45, the mesh cams are provided with timing tabs 218 to positively position the cams on the shaft 169 to insure actuation of the slides as the datum line passes them.

In accordance with the invention, the auxiliary butts

205 on the jacks in group B are extra short, and stop means is provided independently of the mesh cams 123 to position the slides in a partially retracted position out of the path of the auxiliary butts, but the cams operate to position the slides in the path of the short butts at the appropriate positions. The stop means for the independent operation of the slides are operated from the pattern drum.

In the present instance, the stop means for the jack slides 203-1 comprises a pair of bell crank levers 220. Each lever 220 is provided with a pin 221 projecting upwardly and downwardly therefrom to engage the operating levers 216 for the jack slides above and below the lever 220. An operating linkage 223 extends to the pattern drum, is actuatable to engage the levers 216 and prevent their full retracting when the high spot 207 of the associated cam of the cam bank 123 passes beyond the cam follower 214.

The stop means for the mesh slides 203-3 consists of a pair of stop slides 230 connected to the pattern drum by a suitable linkage 231 (see FIG. 3). The slides 230 have enlarged head portions 232, each operable to engage two of the cam followers 211 to prevent full retraction of the slides when the follower disengages the high spot 207 of the associated cam of the cam bank 123.

The operation of the mesh cams 123 to form the mesh pattern shown in FIG. 46 will be apparent by consideration of the cam development shown in FIG. 45 in connection with the jack diagram of FIG. 44. While the mesh fabric is being knitted, the pattern drum operates the linkages 223 and 231 to actuate the stops as required. In the present instance, the drum operates the upper one of the levers 220 to serve to stop the upper two mesh slides, the lower lever being withdrawn to inoperative position. The drum also operates the lower one of the levers 230 to serve to stop the lower two mesh slides, the upper lever being withdrawn to inoperative position. Thus the upper two slides of the group 203-1 and the lower two slides of the group 203-3 are continuously in the path of the long and short butts at their respective levels, and are selectively operated by the cam bank to enter the path of the auxiliary butts. The remaining slides are operated in the conventional way by the cam bank.

With the jack arrangement shown in FIGS. 42, 44 and 47, wherein each of the groups B, C, and D, the jacks are arranged in sets of four, as shown in 42, except, in the present instance, the final set of the group C includes only three jacks, the fourth jack being replaced by the jack 201. The first jack of the group B, i.e., the one adjacent the jack 201, has a short butt 204 at the fourth level and an extra short butt 205 at the second level. The second jack has a butt 204 at the second level and an auxiliary butt 205 at the third level, and so forth. To form the mesh, the jacks of group B enter the selection station comprising the mesh slides 203-1, the first of the slides 203-1 being held by the upper stop means in a position to engage all but the extra short butts 205 at the first level, raising the fourth jack in each set. The second of the slides 203-1 is held by the cam in the fully inserted position to engage both the butts 204 and 205 at the second level, raising the first and second jacks in each set. The third of the slides 203-1 is in transition from a partially withdrawn to a fully withdrawn position, avoiding the short butts 204 and 205. The fourth of the slides 203-1 is in transition to the fully inserted position. Thus, in this portion of the cycle, when the jacks of group B are passing through the selected station, the first and second jacks are raised by the butts 205 and 204 at the second level, the third jack is permitted to pass at tuck level since its butts do not engage any jack slide, the fourth jack is raised by the first slide operating on the butt 204. By the time the jacks of the group B have passed through the station, the fourth slide is inserted to engage the short butts 204 at that level to raise the first jack in each set of group D so the knitting continues with

the third jack providing a tuck stitch. During the succeeding 180° of rotation of the cylinder, the long butts on the jacks raise all but the third jack. In the succeeding 360° of rotation of the cylinder, the first slide is inserted 5 beyond the stop means by the cam as the third slide is in transition, the second slide is held by the stop means to engage all but the auxiliary butts 205. The third slide is in transition to a fully inserted position, and the fourth slide is withdrawn to avoid engaging the short butts, so 10 the first jack is not raised at the slide station comprising the slides 203-1 in a similar manner, and then the cycles are repeated.

The selection station comprising the slides 203-3, is 15 spaced 225° about the cylinder from the station comprising the slides 203-1, and the upper two mesh cams are offset from the lower two mesh cams accordingly. As pointed out above, the stop means is operative on the third and fourth slides to maintain these slides at least at the inserted position engaging the long and short butts 206 and 204. Thus, as shown in FIG. 45, when the first 20 jack of group B reaches the station 203-3, the first slide is in transition to the fully inserted position; the second slide is in transition to a fully withdrawn position, avoiding the short butts 204 and 205; the third slide is held by 25 the stop means to engage all but the extra short butts 205; and the fourth slide is fully inserted beyond the stop means by the cam to engage the extra short butts 205 when the first slide is in transition to the fully inserted position. Thus, the first jack is raised by the fourth 30 slide; the second jack is not raised and passes at tuck level; the third jack is raised by the third slide; and the fourth jack is raised by the fourth slide engaging its butt 205. When the groups D and C pass the station 203-3, the first slide is fully inserted so that the short or long 35 butts 204 or 205 of the first, third and fourth jacks engage the fourth, third and first slides, leaving the second jack at tuck level. Therefore, all but the second jack in each set of the series B, D, and C are raised to clear the associated needles throughout one cycle of the cylinder. 40 In the next 360° cycle, the third slide is fully inserted beyond the stop means by the cam as the second slide is in transition so that all but the fourth jacks are raised. Thus, as described above, during the first course formed 45 at the station 203-1, the third jack tucks. In the first course at the station 203-3, the second jack tucks. In the next course at the station 203-1, the first jack tucks; and in the next course at the station 203-3, the fourth jack tucks. A diagonal mesh is thus formed. By reversing the sequence of jacks to the sequence shown in 50 FIGS. 33-40, a diagonal mesh in the opposite direction may be formed.

In order to deactivate the mesh slides when knitting plain, a drum control linkage 238 operates a cam bank lever 239 to elevate the cam bank 123 in its entirety so 55 as to disengage the followers 211 and 214. All of the stop levers 220 and 230 are operated to an extreme position to enable the followers to clear the mesh cam bank when elevating and lowering the cam bank.

During the formation of the leg and foot portions of 60 the stocking, it is desirable to include a reinforcing patch in the area of the heel as shown at 68 in FIGS. 52 and 53. The insertion of the additional yarns to provide the reinforcing patch is effected by the splicing mechanism 124. To insure a saleable product, the insertion 65 of the reinforcing yarn during each course must be accurately controlled so that the edges of the reinforcing patch areas are sharply defined. In the present instance, the reinforcing yarns are inserted on two of the four feeds, in the illustrated embodiment at the feed stations 111 and 113.

The reinforcing patch is controlled by a ratchet wheel 240 in the splicing mechanism 124. As shown, the ratchet wheel has a dead spot 241 upon which the ratchet 242 normally rests. When it is desired to initiate the 70 formation of a reinforcing patch, the wheel is racked by a

pawl mechanism 243 controlled by a cam 244 on the undersurface of the pattern drum 122, as clearly shown in FIG. 18. The drive for the ratchet mechanism 242 is taken from the splicing cam 158 and is operated to advance the splicing wheel 240, one or more teeth per revolution of the cylinder drive shaft 154. A single revolution of the splicing wheel 240 completes the formation of the contoured reinforced patch or other areas, the contour of which is determined by a contour cam 246 which is adjustable on and rotatable with the splicing wheel 240. The splicing cams 157 and 158 also reciprocate a pair of slides 247 and 248 respectively (see FIG. 20) positioned on opposite sides of a guide bar 250. As shown in FIGS. 24 to 28 inclusive, each slide carries a cam element 256 cooperable with a separate follower elements 256a pivoted to the pattern bar 250 and engaging toggle linkages 253 and 254, best shown in FIG. 27. The toggle linkages 253 and 254 control the reinforcing-yarn feed fingers 115 at the stations 111 and 113 through the cable and push rods shown in FIG. 18. A cam 258 is mounted on the pattern drum to operate levers 259 which retract the feed fingers 115 out of action independently of the splicing mechanism 124. As shown in FIG. 1, a brake is provided for the splicing wheel 240, in the form of a permanent magnet 260 mounted on a strut 261 of the frame 100 to engage the wheel 240. The brake prevents the wheel from over-riding the ratchet and advancing further than the throw of the ratchet mechanism 242.

The present invention provides means for accurately adjusting the splicing cams 157 and 158 to insure proper positioning of the reinforcing patch and to provide proper registry of the initial spliced loop at the feed station 113 with the initial spliced loop at the feed station 111. To this end, the cam 158 is formed with a hub 264 which is minutely adjustable on the cylinder drive shaft 154 by means of the adjusting mechanism 265 shown in FIGS. 18 and 21. The cam 157 is accurately adjustable on the hub 264 as indicated in FIG. 22 so that the angular positioning of the cams may be precisely controlled to correlate with the angular positioning of the feeds 113 and 111. The low point on each cam determines the centerline of the reinforced area formed by the associated feed finger, and the adjustment 265 insures registry of this centerline with the datum line A, on the back of the stocking.

The present invention also provides a novel humidifying device to maintain the supply yarns in proper condition for effectively knitting a stocking. As shown in FIGS. 1 and 2, the yarn supply is contained in a closed cabinet 131 having limited number of openings to atmosphere to permit the yarn from the various packages to pass outwardly therefrom. The cabinet 131 has a bottom wall 290 mounting upstanding yarn supply spindles 295 (see FIGS. 30 and 31) for the yarn packages 135. Overlying the packages 135, the other yarn packages 132 are supported, for example, as indicated at 292 (see FIG. 1). As shown in FIGS. 29 to 31 inclusive, the bottom wall 290 of the cabinet is provided with a plurality of openings 281 which register with a humidifying pan 282 underlying the cabinet and constituting a part of the humidifying device 133. The pan is secured to the bottom of the cabinet by suitable fasteners 284 and is provided with V-grooves 285 in the bottom thereof forming a tree. The V-grooves are triangular in cross section and are of substantially uniform depth, as best shown in FIGS. 30 and 31. An elbow conduit 286 is connected in communication with the grooves 285 and a container of humidifying liquid 287 is mounted in the elbow 286. The container 287 is provided with adjustable mounting means 288 which permits the operator to adjust the height of the mouth 289 of the container and thereby regulate the depth of water in the trough.

Inasmuch as the water or other humidifying liquid in the trough is contained in the V-shaped grooves, any increase in depth in the water will effect a correspondingly

greater increase in the surface area of the liquid in the groove 285. Thus, by adjusting the mouth 289 of the container upwardly or downwardly, it is possible to control accurately the surface area of water in the pan 282. The surface area of the water, in turn, controls the rate of evaporation thereof and this in turn, enables the operator to control the humidity within the cabinet. Thus, the present invention provides a simple but effective apparatus for controlling the humidity of the atmosphere surrounding the supply yarns for the knitting machine.

While a particular embodiment of the present invention has been herein illustrated and described, it is not intended to limit the invention to such disclosure, but changes and modifications may be made therein and thereto within the scope of the following claims.

We claim:

1. In a circular knitting machine for producing a patterned tubular fabric, comprising a rotary needle cylinder, needles and jacks in said cylinder, said needles and jacks having butts of varying length, jack slides and needle cam means engaging the respective butts, and a pattern drum controlling the operation of said needle cam means; a cam bank rotatable with said cylinder operable to control said jack slides, said jack butts including long butts, short butts and auxiliary butts shorter than said short butts, said jack slides being selectively adjustable by said cam bank at each level between an inserted position engaging all of said jack butts at said level, a retracted position avoiding all of said butts, and an intermediate position avoiding said short butts and engaging said long butts, and stop means controlled by said pattern drum independently of said cam bank to position selected slides in a partially retracted position engaging said short butts and avoiding said auxiliary butts, whereby said single cam bank is operable to control said jack slides at two stations spaced circumferentially of the cylinder by displacing said selected slides at each station between said partially retracted and said inserted positions, and displacing the non-selected slides at each station between the inserted, intermediate and retracted positions.

2. A knitting machine according to claim 1 wherein said jack slides and the cams of said cam bank are arranged in groups of four, said stop means being operably connected to said slides in groups of two, whereby a single cam bank and four stop means cooperatively control eight jack slides at two stations to form a pattern in the tubular fabric.

3. A knitting machine according to claim 2 including a pivoted actuator for each jack slide operatively controlled by a cam of said cam bank, said stop means including an element spanning between and engageable with two adjacent actuators to control the latter upon engagement thereof.

4. A circular knitting machine for ladies' hosiery, comprising a rotary needle cylinder and needles and jacks carried thereby, said needles having long and short butts at one level, said jacks having a plurality of butts at at least two levels, at least four feed stations disposed at spaced locations circumferentially of said cylinder, cam means operable to engage said butts to displace said needles between elevated latch-clearing and tuck levels and a lower stitch-draw level, each said feed station including at least one feed finger operable to engage a yarn with the needles disposed at an elevated level at said feed station, means to effect relative rotary travel of said needles and jacks in one direction past said feed stations and cam means, said cam means including a fixed stitch cam and a subsequent fixed elevating cam surface operable upon said needle butts at each feed station, each stitch cam and elevating cam surface in its critical area being identical in contour and mounted against displacement during rotation of said cylinder, said cam means providing a path for the butts of selected needles disposing said selected needles below said elevated latch-clearing and tuck levels immediately in advance of the stitch cams at

at least three of said four feed stations whereby said selected needles are not engaged with yarn at said stations jack slide means cooperable with said path and effective upon the butts of the jacks to select the needles for travel in said path at each of said three stations and a radially displaceable needle cam slide in registry with the jack slide means at each of said three stations, said needle cam slides operable stepwise to engage the needle butts and displace them out of the said path to thereby cancel the selection effected by said jack slides at each of said three stations.
